UNITED STATES PATENT OFFICE

2,019,255

VALVE FOR INTERNAL COMBUSTION ENGINES

George W. Douglas, New York, N. Y., and John Joseph Dewey, Greenwich, Conn., assignors to Articulating Valve Corporation, New York, N. Y., a corporation of New York

Application December 31, 1934, Serial No. 759,922

8 Claims. (Cl. 123—188)

This invention relates in general to valve construction and more particularly to improvements in poppet valves for use in internal combustion engines.

5 It is essential in the operation of an internal combustion engine, that the valves function and seat properly. Such valves, as the poppet type, arranged in the cylinder head are subjected to extreme conditions brought about in the combustion chamber tending toward deterioration of the valve and malfunctioning thereof. These deteriorations take the form of carbon deposits, warping, pits, and unevenness of wear of the valve by its contact with its seat. The results are 10 15 20 25 30 35 40 45 50 55 leaky valves or sticking valves. As long as the valve is pitted or has unevenly distributed carbon deposits, leaking of the valves and loss of compression will result. As long as the valve stem is burdened with unevenly distributed carbon deposits sticking valves will result.

Heretofore it has been the common accepted practice to provide a poppet valve with a unitary stem against which a cam actuated poppet bears to open the valve. A spring is provided to return the valve to its seat subject to the operation of the tappet. The movement of the valve is purely reciprocatory. Now, particularly in connection with the exhaust valve, one side of the valve seat as well as one side of the valve and stem, are being constantly subjected to more extreme heat and a greater tendency to receive carbon deposits than the other sides is present.

It is therefore an object of this invention to provide a valve and an improved means of operating the valve so that in addition to a reciprocatory movement the valve is also slightly rotated during each cycle of operation so that the wear and the carbon deposits and extreme heat will, by reason of the rotation of the valves, be evenly distributed on the valve and its stem. In this manner the valve head will not burn on one side as different parts of the valve are constantly being seated on different parts of the valve seat. This will also tend to eliminate carbon deposits on the valve seat as the movement of the valve will tend to pulverize the carbon.

It is also an object of the invention to provide an arrangement of this nature for the purpose of preventing broken valve springs, by providing an articulated valve stem so that the part directly connected to the valve head will be rotatable relatively to that part of the valve stem which is spring pressed and cam actuated. In this manner the spring will be relieved of the usual sudden shock when the valve drops into its seat.

In the usual design of poppet valve construction in internal combustion engines it is necessary to remove the spring in order to grind or remove the valves. This entails a laborious operation and a checking of the spring when it is replaced to determine its proper functioning when the valve and its spring are again assembled for operation.

In order to avoid these difficulties, it is a further object of our invention to provide a valve and stem, and means of mounting of the same whereby it will not be necessary to remove the spring when removing the valve and further where it is merely necessary to apply the proper tool to the valve head and grind the same against its seat without removing the valve or spring or disturbing the relationship therebetween.

In order to make this possible it is proposed to provide an articulated valve stem, one part of which will receive the spring and be operated by the cam actuated tappet while the other part of the valve stem carries the valve head, the valve head and its adjacent stem portion being reciprocable in unison with but rotatable independently of the tappet actuated stem portion. Furthermore, for valve removal and valve grinding purposes, the abutting portions of the articulated stem may be held in place by a removable coupling so that the upper stem and the head may be removed without disturbing the valve spring.

The objects and nature of our invention will become more apparent on a further reading of the following specification and appended claims, certain embodiments of the invention being shown in the accompanying drawing, in which:

Figure 1 is a fragmentary view in vertical section taken through a cylinder head showing the piston and poppet valve in the combustion chamber;

Figure 2 is a view in elevation partly in section of the poppet valve and its articulated stem prior to the compressing operation to join the two parts together;

Figure 3 is a view similar to Figure 2 of the valve in assembled position;

Figure 4 is a top plan view of the valve head;

Figure 5 is a fragmentary sectional view similar to Fig. 1 showing a modified form of stem in which the articulated portions are held by a removable coupling.

Referring more particularly to the drawing the cylinder 1 and its head 2 is shown with the usual type of combustion chamber 3. The cylinder is shown as provided with the usual type of piston 4 having a connecting rod 5 connected to the piston 55

4 by means of a wrist pin 6. The cylinder may be water-jacketed, as shown at 7, that portion of the jacket 7 adjacent the valve stem guide 8 being slightly enlarged at 9 while the other side of the valve stem guide is water-jacketed, as shown at 10. The usual spark plug 11 is also shown as projecting into the combustion chamber.

For purposes of discussion the valve shown at 12 is referred to as an exhaust valve by reason of the fact that it is the exhaust valve that is subjected to the relatively more strenuous heat conditions. It must be remembered, however, that the improvement constituting our invention is equally applicable to intake valves and therefore our invention consists in improvements as applied to intake as well as exhaust valves.

Referring to Figure 2 the valve head 12 is provided with the usual recesses 13 to receive a suitable tool for grinding operations against the valve seat. The valve head is shown provided with a stem portion 14 which is reduced at 15. This reduced stem may extend downwardly to a point 16. At one or more points in its reduced diameter it may be provided with peripheral grooves, three of which are shown in Figure 2 at 17. The number of grooves provided is merely a matter of choice. The valve stem 14 together with its reduced portion 15 does not constitute the proper length of the valve stem for operating purposes.

It may be of any desired length so as to cooperate with the lower portion shown at 18 to constitute a valve stem of proper operating length. This lower portion 18 of the valve stem is centrally bored so as to snugly but rotatably receive the reduced portion 15. As shown in Figure 2 the upper portion of the valve stem 18 may be enlarged, as shown at 19. In assembling the two parts together it is merely necessary to press the enlarged portion 19 radially inwardly, at which time the smooth inner surface of the enlarged portion 19 will be formed into ribs on projections 20 by being pressed into and fitting in the grooves 17 of the reduced portion 15. The grooves 17 however are not spiral but are exactly perpendicular to the length of the valve stem. It is important and essential that the relationship of the projections 20 and the grooves 17 be such as to allow free relative rotation between the valve stem portions 14 and 18. The enlarged portion 19 is then machined down so as to conform with the outer diameter of the remaining portion of the stem portion 18. The bottom 16 of the reduced portion 15 fits in and bears upon the bottom of the bore in the stem portion 18. The stem portion 18 is also provided with an oil groove 21 extending from the bottom of the stem portion 18 upwardly so as to communicate with the bore which receives the reduced portion 15. The stem portion 18 is also provided with a peripheral groove 22 to receive a washer 23.

In assembling the valve in the internal combustion engines it is merely necessary to push the composite articulated valve stem downwardly through the valve stem guide 8. A compression coil spring 24 may then be placed around the valve stem guide portion 25 so as to rest against the shoulder 26. The valve stem may then be compressed and the washer 23 removably secured to stem 18 by means of groove 22. The coil spring 24 when thus assembled has a tendency to pull the valve head downwardly against its seat 27. The cam actuated tappet for raising the valve off its seat against the action of the compression spring is shown at 28 and may be of any convenient and conventional design.

Due to the flow of the exhaust gases in the combustion chamber, as shown by the arrows, that portion of the cylinder shown at 30 is being subjected to relatively more extreme heat than the remaining sides of the cylinder. The valve 5 head has been generally referred to at 12 and the valve seat has also been generally indicated at 27 but it will be seen that if the valve head remained in this fixed position, other than its reciprocatory movement, that portion of the 10 valve head indicated at 12' would be subjected to relatively greater temperatures and carbon deposits than would the remainder of the valve head by reason of the fact that this portion 12' would be the only portion of the valve head that 15 would be contacting with that portion of the valve seat indicated at 27' and further would always be in the position directly opposing the flow of hot exhaust gases. It follows that the valve stem, if it did not rotate, would also be subjected on its side facing the direction of flow of the exhaust gases to a relatively greater extreme heat and carbon deposits than would the remainder of the valve stem.

However, by the present arrangement, when 25 the tappet 28 pushes upwardly on the valve stem, the compression of the spring 24 tends to slightly rotate the lower portion of the valve stem. While the upper portion of the valve stem is free to rotate with relation to the lower portion 30 of the valve stem, nevertheless a slight rotation is imparted to the valve head due to the twisting action of the spring and a small degree of drag in the relative rotational relationship between the two valve stem components. On the 35 downward movement of the valve stem brought about by the compression spring that portion of the valve head indicated at 12' will contact with a different portion of the valve seat than that from which it has been immediately removed. 40 Likewise the expansion of the spring would tend to give a reverse twist to the lower portion of the valve stem, but the valve head contacts its seat prior to this so the valve head remains advanced on its seat. Moreover, in view of the fact that the 45 valve head is rotatable, it will be free to turn as its seats so as to tend to correct any unevenness on the valve head heating surface as well as the surface of the valve seat.

Thus by reason of the fact that the valve stem 50 and valve head are free to rotate the extreme heat conditions to which they are subjected is evenly distributed throughout all sides thereof. This minimizes and tends to eliminate warping of the valve head and the formation of carbon 55 deposits and pits in the valve head, valve stem or seat. The carbon which would otherwise be deposited on the valve seat will be pulverized by reason of the possible rotary movement of the valve as it returns to its seat under the urging 60 of the compression spring.

As a further refinement tending towards the elimination of sticking valves there may be provided an oil groove 21 up through which oil may flow so as to come between the outer surface 65 of the reduced portion 15 and the inner surface of the lower valve stem 18. Moreover oil in flowing past these adjacent surfaces may also flow out between the slight space between the junction point indicated at 31 between the upper 70 and lower valve portions so as to provide a film lubrication for the composite valve stem within its guide.

It will be readily seen that when it is desired to grind valves it is merely necessary to engage the 75

head portion with a suitable tool and rotate the same after the camshaft has been rotated in such a position that the valve head rests approximately against its seat, leaving, of course, sufficient clearance to receive the valve grinding component. Inasmuch as the valve head and the upper stem portion is rotatable with relation to the lower valve stem portion, such a rotation in the grinding operation may be freely performed without consideration of the compression spring 24. In other words, the grinding operation, as distinguished from the conventional practice, does not entail the removal of the valve spring.

The same holds true in connection with the form of the invention shown in Figs. 5 and 6, in which the valve stem is shown as comprising an upper portion 40 and a lower portion 42. The upper stem 40 is provided with a suitable number 20 of grooves 41 and the lower stem 42 with grooves 43. The stems are placed so as to abut each other and held in place preferably by a removable coupling. The coupling may consist of two semi-cylindrical members 46 and 44 respectively provided with inner flanges 47 and 45 each to engage the grooves 41 and 43 of the stems to prevent relative vertical displacement but permit relative rotational movement. When assembled, the coupling may be affixed by means of screw bolts 30 48 or the like. As shown, the coupling, when the valve head is in its highest operating position, will not come into contact with the valve stem guide and consequently the coupling will not interfere with the proper operation of the valve. In 35 order to remove the valve head and the upper stem, integral therewith, it is merely necessary to remove the coupling and then pull upwardly, on the head. In doing so it is not necessary to remove the spring. When the valve head and 40 stem are replaced this also may be done without disturbing the spring. It is, of course, understood that the releasable coupling may be formed of such size as to have its diameter equal to that of the two valve stem portions so that it may be 45 free to slide in the valve stem guide. This may be accomplished in a similar manner to that discussed in connection with element 18 in Fig. 2. In this manner or by coupling the stems directly 50 together without the extra sleeve, the point of coupling may be above the stem guide when the valve is pulled manually upwardly for removal purposes.

Furthermore this arrangement tends toward the elimination of broken valve springs inasmuch as the valve head is free to rotate as it seats and comes into contact with the seat before the extreme lower point of movement of the valve stem and thus the spring is not subjected to the usual sudden stop when the valve engages its seat. Furthermore the camshaft for operating the tappet may turn freely as there is no binding in the valve head inasmuch as there is no positive twisting connection between the spring and the valve head, or in other words because the 65 valve head is rotatable with respect to the spring.

As previously stated the wear on the valve stem by reason of the cam action on the lifting operation will be evenly distributed insofar as the upper portion of the valve stem is concerned and consequently there will be less tendency towards valve stem guide leakage. Furthermore by reason of the slippage provided for in the valve stem, the valve will not chatter as it seats.

We claim:

1. In a valve comprising a valve head, an articulated valve stem one portion of which carries said valve head and is rotatable with respect to the other stem portion but reciprocable in unison therewith.

2. In combination in a valve having an articulated stem one portion of which carries said valve head and which is reciprocable in unison but relatively rotatable with respect to another portion of said valve stem, a seat for said valve, means for actuating said first stem portion for raising the valve off its seat, and spring means connected to said second stem portion for returning the valve to its seat.

3. In combination in a valve having an articulated stem one portion of which carries said valve head and which is reciprocable in unison but relatively rotatable with respect to another portion of said valve stem, a seat for said valve, means for actuating said second stem portion for raising the valve off its seat, and spring means connected to said second stem portion for returning the valve to its seat and for rotating said valve during its reciprocatory movements.

4. In combination in an internal combustion engine, a valve and a valve seat, said valve having an articulated valve stem one portion of which carries said valve and is rotatable with relation to but reciprocable in unison with another portion of said valve stem, a spring for returning the valve to its seat, said spring being connected to said second valve stem portion and otherwise dissociated from the valve and said first valve stem portion.

5. In a valve comprising a valve head, an articulated valve stem one portion of which carries said valve head and is rotatable with respect to the other stem portion but reciprocable in unison therewith and a coupling means for removably holding said portions together.

6. In combination in a valve having an articulated stem one portion of which carries said valve head and which is reciprocable in unison but relatively rotatable with respect to another portion of said valve stem, a seat for said valve, means for actuating said first stem portion for raising the valve off its seat, spring means connected to said second stem portion for returning the valve to its seat, and a coupling means for removably holding said portions together.

7. In combination in a valve having an articulated stem one portion of which carries said valve head and which is reciprocable in unison but relatively rotatable with respect to another portion of said valve stem, a seat for said valve, means for actuating said second stem portion for raising the valve off its seat, spring means connected to said second stem portion for returning the valve to its seat and for rotating said valve during its reciprocatory movements, and a coupling means for removably holding said portions together.

8. In combination in an internal combustion engine, a valve and a valve seat, said valve having an articulated valve stem one portion of which carries said valve and is rotatable with relation to but reciprocable in unison with another portion of said valve stem, a spring for returning the valve to its seat, said spring being connected to said second valve stem portion and otherwise dissociated from the valve and said first valve stem portion, and a coupling means for removably holding said portions together.

JOHN JOSEPH DEWEY,
GEORGE W. DOUGLAS.
